UNITED STATES PATENT OFFICE.

OBADIAH BUTLER, AMOS MORIN, AND CHARLES J. LOWRY, OF DANIELSON,
CONNECTICUT.

ELECTRIC STOP MOTION.

Application filed February 9, 1924. Serial No. 691,819.

To all whom it may concern:

Be it known that we, OBADIAH BUTLER, AMOS MORIN, and CHARLES J. LOWRY, all citizens of the United States, residing at 5 Danielson, in the county of Windham and State of Connecticut, have invented new and useful Improvements in Electric Stop Motions, of which the following is a specification.

10 This invention relates to certain new and useful improvements in an electric stop motion particularly adaptable to spinning, twisting and doubling machines.

The object of this invention is to provide 15 a construction wherein the yarn normally holds a circuit closing part inoperative, which part becomes operative upon the breaking of yarn to close a circuit and effect a stopping of the machine.

20 In the drawings:

Figure 1, is a top plan view of a fragment of a machine embodying the present invention;

Figure 2, is a side or front elevation 25 thereof;

Figure 3, is an end elevation thereof;

Figure 4 is a view of the lock for normally holding the belt shipper mechanism operative; and

30 Figure 5 is a detailed section thereof on line 5-5 of Figure 4.

The frame 1 has standards 2 provided with journal bearings 3 in which the beam is mounted. From the beam, the yarn passes over an upper roller 4, journaled in a bracket, arrangement 5 projecting outwardly from the standards, and thence downwardly through guides 6 and 7 and about interposed rollers 8 journaled in uprights 9.

40 Power is supplied to the yarn machine through a disconnectible drive, such as a belt or clutch, the mechanism for shifting the belt to and from a tight pulley or for manipulating the clutch, including a shipper rod or bar 10 which is normally urged to disengage the drive by a spring 11 that is compressed between a fixed part of the machine frame and a collar 12. The shipper rod is equipped with an arm 13 slotted 45 to have sliding connection with an operat-

ing lever 14 by which the shipper rod may be moved against the compression spring to start the machine, a latch 15 being carried by the rod to engage an automatically releasing keeper 16 upon the breaking of 55 the yarn.

The mechanism for effecting this automatic release of the shipper rod to stop the machine, is electrical in its nature and includes a pair of circuit wires 17 having 60 portions extending along the upper unit, comprising the roller 4 and bracket 5, and other portions extending along the lower unit, comprising the guides 6 and 7 and rollers 8. Drop wires 18 are pivoted at one 65 end to one circuit wire in the upper unit for having their opposite ends drop across the companion circuit wire to close a circuit, the several drop wires being normally held elevated by the tensioned yarns which 70 pass through terminal eyes 19 on the several drop wires.

Similar drop wires 20 are likewise pivoted to a circuit wire in the lower unit and equipped with terminal eyes 21 through 75 which the tensioned yarns pass for holding the drop wires elevated above the companion circuit wire. Obviously, if any yarn thread breaks, the corresponding drop wires 80 will drop onto the underlying companion circuit wire to close the circuit for stopping the machine. The circuit includes a source of electrical energy 22, a switch 23 and an electro-magnet 24.

The keeper 16 is substantially right angular in shape, being pivotally mounted at 85 25 and provided with a keeper shoulder 26 which is normally urged to its operative position in the path of the latch 15 by a spring 27 coiled about the pivot 25. The depending 90 arm of the keeper is engaged in a peripheral recess 28 of a tumbler cylinder 29 which is provided with a weight 30 normally tending to rotate the cylinder counter-clockwise. The cylinder is also provided with an upwardly extending arm 31 which is held 95 against the armature 32 of the magnet 24 by the weight 30, said arm being formed with a recess or notch 33 opposite which the armature is attracted by its magnet whereby 100

the arm may swing counterclockwise. This movement of the arm 31 and consequent rotation of the cylinder 29 is sufficient to release the keeper out of the peripheral recess 28 and release the latch 15. Consequently, when a yarn thread breaks, the circuit through the magnet will be closed, which effects the release of the catch 15 and the expansive force of the spring 11 will move the shipper rod to stop the machine.

Upon the shutting down of the mill and the stopping of the machinery, the shipper rod is moved to shift the belt over to the loose pulley, or disconnect the clutch if the latter is used. Simultaneous with this operation, it is desirous to break the electric circuit which is accomplished by opening switch 23. To effect this, an arm 34 is fixed on the shipper rod having a pin and slot connection with an arm 35 fixed on shaft 36 which carries a switch arm 37 constituting the movable element of the switch 23. As the shipper rod is moved to the right the switch arm is swung to break contact and consequently, open the circuit.

In operation, it will be clear that upon the breaking of a yarn thread the corresponding drop wires, which are in the nature of switches, will close the circuit to release the shipper rod. As the latter is shifted by the spring 11 to stop the machine the switch 23 is also opened. After the broken yarn has been again connected the operator manipulates the lever 14 to start the machine, the latch 15 being engaged with its keeper to hold the shipper rod against the tension of spring 11.

Having thus described our invention, what we claim as new and desire to secure by Letters Patent is:—

1. A stop motion mechanism including a longitudinally movable shipper, means urging it to inoperative position, a latch carried by the shipper, a keeper engageable by the latch to hold the shipper operative, a gravity operated tumbler for holding the keeper operative, an electromagnet having an armature normally arranged in the path of the tumbler for arresting the same, and means operable upon the breaking of a thread for closing a circuit through the magnet.

2. A stop motion mechanism including a longitudinally movable shipper, means urging it to inoperative position, a latch carried by the shipper, a keeper engageable by the latch to hold the shipper operative, a gravity operated tumbler for holding the keeper operative, an electromagnet having an armature normally arranged in the path of the tumbler for arresting the same, a circuit including the electromagnet, a normally closed switch included in the circuit, and

means operable by the shipper for opening the switch.

3. A stop motion mechanism including a longitudinally slidable shipper, means urging it to inoperative position, a latch pivotally carried by the shipper, and having a downwardly extending nose on its free end, a keeper engageable by the latch nose to hold the shipper operative, a gravity operated tumbler for holding the keeper operative, an electromagnet having an armature normally arranged in the path of the tumbler for arresting the same, and means operable upon the breaking of a thread for closing a circuit through the magnet.

4. A stop motion mechanism including a longitudinally movable shipper, means urging it to inoperative position, a latch carried by the shipper, a keeper engageable by the latch to hold the shipper operative, a gravity operated tumbler for holding the keeper operative, an electromagnet having an armature normally arranged in the path of the tumbler for arresting the same, a circuit including the electromagnet, an arm fixed on the shipper, and a lever engaging the arm to move the shipper against its spring means to engage the latch with the keeper.

5. A stop motion for yarn machines, comprising a shipper element, a keeper for holding the same in a power-connected position, electrical means for rendering the keeper inoperative, an electric circuit including said means, a plurality of drop wires connected to one side of the circuit and formed with eyes through which the yarn threads pass for holding the wires elevated, each of said wires adapted to drop upon the breaking of a respective yarn thread to close with the other side of said circuit, a switch included in the circuit and embodying a rotary contact, and means connecting the contact to the shipper element for rotating the contact to break the circuit.

6. A stop motion for yarn machines, comprising a shipper element, a keeper for holding the same in power-connected position, electrical means for rendering the keeper inoperative, an electric circuit including said means, a plurality of drop wires connected to one side of the circuit and formed with eyes through which the yarn threads pass for holding the wires elevated, each of said wires adapted to drop upon the breaking of a respective yarn thread to close with the other side of said circuit, a switch included in the circuit and embodying a contact, a rock shaft having a pair of arms one arm carrying the contact, and means on the shipper element for moving the other arm to rock the contact to open position.

7. A yarn machine stop motion comprising

means movable for stopping the machine, an electric circuit closable upon the breaking of a yarn thread, a pivoted keeper for holding said means against movement, a tumbler for holding the keeper operative, and electro-magnetic means in the circuit having an armature for rendering the tumbler inoperative to release the keeper.

In testimony whereof we have signed our

names to this specification in the presence ¹⁰ of two subscribing witnesses.
